FOLDING AND SEALING MECHANISM FOR
WRAPPING MACHINES

Arthur A. Kottmann, Davenport, Iowa, assignor, by mesne assignments, to American Machine & Foundry Company, New York, N. Y., a corporation of New Jersey

Original application October 6, 1950, Serial No. 188,686. Divided and this application February 28, 1952, Serial No. 273,942

12 Claims. (Cl. 53—149)

1

This invention relates to wrapping machines of the type in which the leading end of a web of wrapping material is applied to an article to be wrapped as the article is moved from a feed runway onto an elevator, and in which the web is wound about the article and folded against the ends of the article during movement of the elevator, transfer of the articles from the elevator to a discharge runway, and movement along the said discharge runway, and particularly to the final folding and sealing mechanism of the machine, the present application being a division of my copending application Serial No. 188,686, filed October 6, 1950.

In the machine of the present invention the articles, with a thermoplastic coated wrapper wound around them, are passed from an elevator into a folding and sealing channel where the end folds are formed in the wrapper and the thermoplastic coating of the overlapping portions of the wrapper are fused and adhered together. The wrapped packages then pass into a cooling section where the fused coatings are solidified to complete the sealing of the package.

One object of the invention is to protect the article and wrapper feeding mechanism that is positioned beneath the sealing channel from the heat generated in the sealing channel.

A further object is to provide a folding and sealing channel so constructed that the operations can be viewed by the operator and having parts movable to permit quick access for removal of any improperly positioned or improperly wrapped articles.

A further object is to provide the discharge runway with article moving conveyors and guides which maintain the articles in proper position during their passage through the runway.

A further object is to mount all guides and conveyors on parallel side rails which are adjustable to accommodate articles of different sizes and to support the adjustable side rails independently of their adjusting screws so that the screws are not flexed by the weight of the conveyors and guides.

Reference should be had to the accompanying drawings forming a part of this specification, in which:

In the wrapping machine of the present invention the articles to be wrapped are delivered to the wrapping mechanism by means of an endless pusher flight conveyor A which delivers to a vertically swinging elevator or transfer platform B. The infeed conveyor A delivers the articles to be wrapped onto the elevator B and in passing from the conveyor A to the elevator B the articles engage with the leading end of a web of wrapping material which is suspended from a drape table C over which the wrapping material is fed.

The feed conveyor A is mounted in an inclined position and delivers the articles from its upper end to the elevator B which moves from an inclined receiving position in alignment with the conveyor A to an upper horizontal position in alignment with a discharge runway which includes a folding and heating section D and a cooling section E to complete the wrapping of the article and seal the folds of the wrapper.

The wrapping machine may be conveniently operated in tandem with a bread slicing machine such as the bread slicing machine F shown diagrammatically in Fig. 3, the slicing machine having a delivery conveyor G which delivers the sliced loaves to the infeed conveyor A of the wrapping machine by means of a suitable shuttle mechanism H interposed between the conveyors G and A.

A web of wrapping material is fed to the drape table C from a reel rack K through a tension controlled web feed mechanism L. During each wrapping cycle the leading end of the web of wrapping material is suspended between the delivery end of the feed conveyor A and the elevator B where it is engaged by the article to be wrapped and clamped between the article and elevator so that a pull is exerted on the web to create tension therein and cause actuation of the feed mechanism to supply the length of web needed for wrapping the article.

The article being wrapped is discharged from the elevator and moved through the folding and sealing sections of the discharge runway by means of an overhead endless pusher conveyor M. The bottom of the cooling section E is formed by an endless belt N and the sides by two endless belts P which grip and travel with the wrapped article during cooling so that lapping portions of the wrapper are held against relative movement while the wax or other adhesive is setting.

The feed conveyor A is intermittently driven

with a dwell during upward movement of the elevator B and the elevator is reciprocated with a dwell at its upper and lower limits of movement. The overhead pusher conveyor M and conveyors N and P are continuously driven.

The machine has a frame 1, the top of which is horizontal to provide a support for the article discharge runway.

The machine is driven by an electric motor 2 which continuously drives a main cam shaft 3 and a feed conveyor driving shaft 4 through a sprocket chain 5. A shaft 6 which drives the shuttle mechanism H is driven from the shaft 4 through a sprocket chain 7. The overhead pusher conveyor M is driven from the shaft 3 through a sprocket chain 8 and a sprocket 9 that operates the web feed mechanism L is driven from the shaft 3 through a sprocket chain 10. The belt N is driven by the sprocket chain 10 through gears 11 and the belts P are driven by the endless pusher conveyor M through bevel gears 12. When the wrapping machine is operated in tandem with the slicing machine F the slicing machine and its discharge conveyor G are driven from the shaft 6 by a sprocket chain 13.

In order to avoid slack between the article being wrapped and the web feed mechanism and in order to reduce slack and obtain more uniform control of the web feed to articles varying in height, the drape table C is adjustably mounted so that its upper end can be positioned at different distances above the discharge end of the infeed conveyor A so as to obtain a more direct pull on the paper and a better regulation of the web feed and also to avoid delivery of an excess amount of wrapping material to low articles.

The table C, which is mounted directly above the conveyor A, is pivotally and slidably supported at its lower end on a bracket 15 carried by the frame of the machine, and is adjustably supported intermediate its ends upon brackets 16 attached to the top portions of the frame 1, the table adjusting mechanism being so designed that an operating connection between the web cut-off mechanism carried by the main frame and paper clamping mechanism carried by the table C is not disturbed by the adjustment.

The machine is so designed that all manually operable adjusting and controlling elements are mounted on the front side of the machine in positions conveniently accessible to an operator standing at the front of the machine. A hand lever 17 mounted on the front end of the frame controls the operation of the feed conveyor A and the slicing machine F and conveyor G when the slicer is mounted in tandem with the wrapping machine. A handwheel 18 adjacent the rear end of the machine controls the speed of operation of the machine. A handwheel 19 associated with a dial 20 may be adjusted to control the amount of wrapper web drawn out from the drape table prior to the web cut-off to vary the length of the end of the web depending from the upper end of the drape table C and vary the amount of underlap of the paper at the bottom of the article being wrapped. A handwheel 21 associated with a dial 22 may be adjusted to control the tightness with which the paper is wrapped about an article. Heater control elements 23 are mounted on the top portion of the frame forwardly of the tight-loose wrap control. Adjacent the rear end of the machine a handwheel 24 is provided which operates adjusting screws for adjusting the width of the discharge channel of

the machine and simultaneously adjusting other parts of the machine for accommodating articles of different widths.

The feed conveyor A is provided with a transversely flat bed 25 over which the articles to be wrapped are pushed by flights 26 which are carried by endless sprocket chains 27 that run over pairs of sprockets 28 and 29 at the delivery and receiving ends of the bed 25. The pairs of sprockets 28 and 29 are preferably mounted in fixed positions and the chains 27 are tensioned by means of adjustable sprockets 30 below the sprockets 29 at the forward end of the frame.

The conveyor A is driven intermittently and the chains 27 are moved a distance corresponding to the space between successive flights 26 on each actuation, the driving mechanism being so adjusted that the conveyor stops with a flight 26 in substantially vertical position at the discharge end of the conveyor, in which position the article being pushed by the flight at the discharge end of the conveyor has been transferred from the bed 25 to the elevator B, and the flight 26 at the discharge end of the conveyor remains stationary during the initial upward movement of the elevator and does not interfere with the movement of the article with the elevator.

The infeed conveyor A is intermittently driven from the shaft 4 through a Geneva type gearing which includes a drive wheel 44 fixed to the shaft 4 and having two driving pins in the form of rollers 45 which are diametrically opposite each other and at equal distances from the axis of the shaft 4. The rollers 45 engage in radial slots 46 in a Geneva gear 47 to which is attached a spur gear 48 which meshes with a gear 49 on the shaft of the sprockets 28. The gear 47 is provided with four radial slots 46 and is given a quarter turn upon each half revolution of the shaft 4. The gear 47 is provided with peripheral recesses 50 intermediate the slots 46 which are of arcuate contour to receive cylindrical locking segments 51 carried by the drive wheel 44 to lock the gear 47 against turning movements during intervals between actuations thereof by the pins 45.

The sprocket 42 on the shaft 4 is twice the diameter of the sprocket 41 on the shaft 3 so that the shaft 4 rotates at half the speed of the shaft 3. The shaft 3 rotates once during each cycle of operation of the machine and the shaft 4 makes a one-half revolution during each cycle of operation.

The gears 48 and 49 are so proportioned that a movement is imparted to the infeed conveyor A to move the flights a distance exactly equal to the length of the space between them upon each actuation of the conveyor, and the infeed conveyor has one movement during each wrapping cycle to deliver an article to the elevator B each time that the elevator is lowered to a position in alignment with the conveyor.

The article feed conveyor A has parallel side guide rails 72 that are connected for simultaneous adjustment by transverse screw shafts 74 and 77. The shafts 74 and 77 are driven by the handwheel 24 through a sprocket chain 78.

The sliced loaves of bread or other articles to be wrapped are delivered from the feed conveyor A to a platform 105 on the elevator B, the platform 105 being attached to the forward ends of elongated supporting arms 106 that are connected at their rear ends by pivots 107 to the rocker arms 14 which provide a movable support to which the elevator is pivoted. The arms 106 are connected to the upper ends of the rocker arms 75

14 and the lower ends of the arms 14 are attached to a horizontal rock shaft 108 journaled in the side members of the frame. During operation of the machine the elevator platform moves from a lower inclined position in alignment with the bed 25 of the infeed conveyor to an upper horizontal position in alignment with the discharge runway. The elevator dwells in its lowermost position until an article is transferred thereto by the infeed conveyor, and moves upwardly during the dwell of the infeed conveyor to deliver the loaf to the discharge runway. The elevator has intermittent oscillating movement timed with respect to the movement of the infeed conveyor flights 26 so that the elevator is positioned to receive articles pushed by the flights 26 during each advancing movement of the feed conveyor. During the upward movement of the elevator the arms 14 are rocked rearwardly to cause the forward end of the elevator on which the article being wrapped is supported to be moved away from the infeed conveyor flight and away from the end of the drape table C so that tension is maintained on the wrapper web and engagement 20 of articles being wrapped with parts of the paper supporting members and with the discharge runway is prevented. Springs 109 attached at their rear ends to the rocker arms 14 and at their forward ends to the frame of the machine serve to 25 yieldably urge the elevator toward its forward position.

The machine frame has a horizontal crossbar 110 at the rear end thereof upon which is mounted a bearing bracket 111. The bracket 111 supports a pivot 112 upon which is mounted a lever 113 which extends forwardly from the pivot 112. The forward end of the lever 113 is pivotally connected to the lower ends of links 114, and the upper ends of the links 114 are pivotally connected to the elevator.

As shown in Fig. 5, the drape table C is provided with a pair of web guiding rollers 134 and 135 at the rear end thereof. While the elevator is in its uppermost position and before the wrapper strip is severed the web is advanced sufficiently to provide enough of the leading end of the web beyond the roller 134 to extend into the space between the elevator platform and bed 25 of the infeed conveyor when the elevator platform is returned to its lowermost position. As the infeed conveyor moves the article to be wrapped across the gap between the bed 25 and the platform 105 the article is pushed into the depending end of the wrapper web and the portion of the web depending below the elevator platform is drawn onto the platform between the bottom of the article and the surface of the platform.

In order to clamp the leading end of the web to the article being wrapped, a follower 136 is provided on the elevator platform which is mounted to move forwardly and rearwardly on the platform. The forward article engaging end of the follower 136 is attached to a rearwardly extending guide bar 137 and extends transversely across the elevator platform and slides rearwardly on the platform as an article is pushed onto the platform by a flight 26.

As the article to be wrapped is transferred to the elevator platform from the bed 25 the wrapper web is folded against the ends of the article by means of tucker plates 148 which engage with the opposite edge portions of the web to fold the side edge portions of the web over the ends 75 of the article during movement of the article

onto the elevator. The tucker plates 148 are mounted for lateral swinging movements and are so operated that they close upon the ends of the article being wrapped during movement of the article onto the elevator.

When the article to be wrapped is pushed by a flight 26 onto the elevator platform 105 it engages the leading end of the wrapper web that is suspended from the roller 134, clamps the web against the follower 136 and drags the end thereof over the forward edge of the platform 105 and into engagement with its bottom. At the same time the tuckers 148 fold the opposite side portions of the web against the ends of the article. During upward movement of the elevator the web is wound over the top and down the front of the article, being guided by the roller 135 as shown in Fig. 5.

As shown in Fig. 7, the elevator platform 105 is aligned with the discharge runway D when the elevator is in its uppermost position, and the article on the elevator is moved from the elevator platform onto the discharge runway by means of the endless conveyor M which has pusher plates 210 carried by arms 211 that are suspended from endless sprocket chains 212 mounted above and parallel to the discharge runway. The sprocket chains 212 run over rear sprockets 213 that are positioned directly above the elevator, the sprockets 213 being attached to a horizontal cross shaft 214 that is driven from the cam shaft 3 by the sprocket chain 8. The endless pusher conveyor M above the discharge runway is thus continuously driven during the operation of the machine and the movement of the pushers is timed with respect to the operation of the elevator so as to discharge each article from the elevator to the discharge runway during the dwell of the elevator in its uppermost position.

At the end of the discharge runway, immediately adjacent the elevator, a paper feed roller 215 is provided against which the rollers 176 on the elevator are pressed by the springs 109 when the elevator is in its uppermost position and which may be driven during a portion of the movement of the article from the elevator to the discharge runway to regulate the tightness of the wrapper. When the elevator is in its uppermost position, a shear bar 178 carried by the elevator below the roller 176 is in position to contact with a movable knife blade 216 carried by swinging arms 217 to sever the web.

In order to feed enough of the wrapper web past the drape table C prior to severance of the web to cause the leading end of the web to be draped across the upper end of the bed 25 of the feed conveyor and to regulate the feed to cause the web to extend below the bed the distance required to provide the desired underlap beneath the article when the web is clamped thereto on the elevator, means is provided for automatically causing the desired length of paper to be fed past the upper end of the drape table prior to severing the web. The web feed is controlled to supply the drape by means of a tension applying roller 254 that is supported in horizontal position between the upper ends of two curved arms 255 which are positioned immediately within the side members of the machine frame 1 in the space between the side members and the conveyor A, elevator B and drape table C. The roller 254 is normally supported forwardly of the rear edge of the discharge runway so as to be clear of the paper web when it

is drawn upwardly to the position shown in full lines in Fig. 5. The lower ends of the arms 255 are fixed to a transverse rock shaft 256 that is journaled in the side frame members. At the 5 end thereof adjacent the front of the machine, the shaft 256 has a downwardly projecting arm 257 that is connected by a link 258 to an adjustable lever arm 259 that is slidably mounted in a lever body 260 that is attached to a horizontal shaft 261.

The lever body 260 is provided with a guide portion 264 in which the extension 259 is slidably mounted, and the lever is oscillated once during each cycle of the machine by means of a cam 265 on the shaft 3 that has a groove 266 to receive a roller 267 mounted at the upper end of the lever 260. The lever extension 259 is provided with rack teeth 268 that engage with a pinion 269 that is attached to the tubular shaft 262. The cam 20 265 actuates the lever 260 to swing the arm 267 rearwardly and move the tension applying roller 254 rearwardly and downwardly prior to the severance of the web. The pull exerted by the roller 254 on the web actuates the tension sensitive 25 control of the feed mechanism L to cause the web to be fed toward the wrapping mechanism to supply the length of web necessary to form the drape for the next article to be wrapped. The length of web so advanced is regulated by 30 adjustment of the lever arm 259, which can be extended or retracted by means of the pinion 269 to increase or decrease the throw of the roller 254.

In order to enable the articles to be transferred 35 from the elevator to the discharge runway by means of the continuously driven overhead conveyor M which moves the articles at the desired speed through the folding and sealing channels, means is provided for accelerating the movement 40 of the pushers 210 during their travel across the elevator platform and then decelerating their movement in order to discharge the article on the platform during the small portion of the wrapping cycle in which the platform is aligned with 45 the discharge runway, and then moving the articles below normal speed during a portion of their travel through the folding channel. These accelerating and decelerating movements are caused by imparting a forward swinging movement to 50 the pusher supporting arms 211 past their normal position during their engagement with the article on the elevator platform followed by a rearward swinging movement back to normal position. The arms 211 have short end portions 380 adjacent the chains 212 that extend at substantially right angles thereto, the end portions 380 being connected to the chains 212 by pivots 381. The arms 211 are arranged in pairs which are transversely aligned, the transversely aligned arms 211 being attached to the front and rear chains 212 and being disposed upon the inner sides of the chains 212.

As shown in Fig. 8, each of the sprockets 213 has an elongated hub 382 that is slidably keyed to 65 the driven cross shaft 214. The elongated hubs 382 provide support for collars 383 which are attached to the side rails 158 of the discharge runway. As shown in Figs. 6 and 7, the chains 212 run over front sprockets 384 on aligned stub shafts 70 385 that are mounted on the guide rails 158.

The lower run of each of the sprocket chains 212 is guided in a slot between superposed bars 386 and 387 attached to the inner face of a longitudinal supporting bar 388 that is attached to 75 a side rail 158 and that has a groove 389 along

its inner face to provide clearance for the chains. Spaced inwardly from each of the chain guide bars 386 and 387 there is a cam rail 390 that has an outwardly facing groove 391 that receives rollers 392 mounted on the pusher arms at the bends thereof. The cam rail has an enlarged rear end portion 393 that is supported on the shaft 214. The forward ends of the cam rails 390 are supported by brackets 394 attached to the bars 388 and the rear ends of the rails are connected to the bars 388 by bolts 395 passing through spacer sleeves 396 interposed between the bars 388 and rails 390. The cam rails 390 terminate near the front sprockets 384 allowing the arms 211 to hang freely from the sprocket chains during their passage from the lower run to the upper so that they are swung by gravity into engagement with pins 398 projecting inwardly from sprocket chains 212. During their passage along the upper run of the conveyor, the chains 212 are supported on guide rails 399. Hold-down bars 400 suitably attached to the side rails 158 overlie the chains 212 adjacent the rear sprockets 213. At the rear end of the cam rails the grooves 391 extend upwardly around the rear side of the drive shaft 213 to guide the pusher arms during their downward movement toward article engaging position, the rear end portion of the cam rail having an inclined portion 397 to guide the rollers upwardly into the groove 391.

The portion of the cam groove 391 below and to the rear of the shaft 214 is deflected upwardly at 406 toward the shaft 214 to swing the pusher arms 211 rearwardly and bring them to substantially vertical position over the rear edge of the elevator platform. During movement of the pusher plates 210 across the elevator platform the arms 211 are swung forwardly past their normal position to increase the speed of the pusher plates and effect a rapid transfer of the article being wrapped to the discharge runway after which the arms are swung rearwardly to their normal position which results in a reduction of speed of the article in the entrance end of the folding section. The pusher arms 211 are first swung rearwardly by the shifting of the arm supporting rollers 392 to positions above the chains 212 in upwardly deflected portions 406 of the cam grooves 391. The forward swinging movement of the arms is accomplished by shifting the rollers 392 to positions below the chain and the rearward swinging movement of the arms is effected by returning the rollers 392 to positions in horizontal alinement with the sprocket chains 212, the rates of acceleration and deceleration being dependent upon the relative inclinations of the chain guides and cam grooves.

The conveyor chains 212 are driven at a speed such that they move a distance corresponding to the distance between successive pusher arms 211 during each wrapping cycle. By means of the cam grooves and chain guides the pushers 210 are caused to move across the elevator platform at a speed greater than the speed of the conveyor chains to transfer the article from the elevator during the small portion of the wrapping cycle that the platform dwells in alinement with the discharge runway. The accelerated movement of the arms 211 is followed by a decelerated movement which causes the article to move relatively slowly in the discharge runway until the arms 211 resume their normal position. This slow movement is advantageous in that it insures proper engagement of the bottom fold of the wrapping paper with the slots in the folding

channel and causes the folds of the wrapper to be effectively heated and sealed in the folding channel. The elevator discharging mechanism is claimed in the application of Edward G. Schrage, Serial No. 183,791, filed October 6, 1950.

As the elevator moves upwardly the wrapper web is wound over the top of the article and projects horizontally past the ends of the article. As the elevator approaches its uppermost position the ends of the wrapper projecting past the article at the top thereof are engaged by vertical folder plates 410 that fold these projecting ends down against the ends of the article as shown in Fig. 14.

15 The top end folder plates 410 are preferably provided with outwardly projecting flanges 411 along their lower edges to provide rounded corners for engagement with the wrapper web. Above the flanges 411 the folder plates may be

20 provided with windows 412 which enable the operator to more quickly detect wrinkles or other defects in the wrap. Forwardly of the top end folder plate 410 and in alinement therewith are bottom end folder plates 413 that engage with the

25 portions of the web projecting past opposite ends of the article at the bottom thereof to fold these portions upwardly against the ends of the article, each of the folder plates 413 being provided with an inclined slot 414 extending upwardly and rearwardly from its bottom edge to receive the folds of the wrapper that project outwardly from the ends of the article at its bottom and to guide the same upwardly and against the ends of the article.

30 35 The top end folder plates 410 are supported by longitudinal bars 415 that are attached at their forward ends by bolts 416 to the folder plates 413 and to the bars 415 by bolts 417. The folder plates 410 are adjustable on the longitudinal bars 415 by means of transversely extending slots 418 in top flanges 419 of the plates through which the attaching bolts 417 extend. Each of the folder plates 413 is connected at its forward end by a vertical hinge 420 to a bracket

40 45 50 55 421 attached to the side rails 158. The hinges 420 permit the folder plates to be swung outwardly to afford access to the elevator and to the entrance end of the discharge runway.

To detachably lock the folder plates in their operative position, a lock plate 422 is attached to the rear end of the bar 415 and projects rearwardly therefrom, being provided at its rear end with a horizontal slot 423 which receives a locking member in the form of an eye bolt 424 that is pivoted to a bracket 425 attached to the side rail 158.

55 60 65 70 75 A thumb nut 426 on the bolt 424 engages with the outer face of the lock plate 422 to retain the folder plates in operative position. The lock plate 422 engages with an adjustable abutment in the form of a screw 427 which is threaded in the bracket 425 and which may be adjusted to increase or decrease the width of the space between the rear ends of the top folder plates 413 and between the rear ends of the folder plates 413. The folder plates 410 can be adjusted by means of the bolts 417 and slots 418 to position them in parallel relation after angular adjustment of the plates about the hinges 420.

The screws 427 are preferably so adjusted that the space between the folder plates 413 at their rear ends is slightly greater than at their forward ends so that pressure on the ends of the article is gradually increased as the article is moved from the elevator into the discharge run-

11

way. The folder plates 413 have outwardly curved rear edges 428 which provide a bell mouth for engagement with the forward corners of the article being wrapped as the article is being pushed onto the discharge runway. The adjustments of the nut 426 and abutment screw 427 determine the amount of rearward flare of the folder plates 413. Since some clearance is necessary between the top folder plates 410 and the tucker plates 418, there is a slight relaxation of pressure on the end of articles being wrapped when the tucker plates are withdrawn. The angular disposition of the folder plates 413 serves to reestablish a pressure corresponding to that applied by the tucker plates and the adjustment regulates the amount of pressure exerted on the ends of the article in the folding and sealing channel.

A pin 429 may be provided on the bracket 425 for engagement in the slot 423 to take the weight of the hinged folder plate off the eye bolts 424. Heaters 420 attached to the folder plates 410 and 413 supply heat to the wrapper folds to cause them to adhere together.

As shown in Figs. 6, 7 and 15, the bed of the folding and sealing section D is in the form of a detachably mounted unit and is carried by a frame having side bars 432 attached by bolts 433 to the side members of the frame, front and rear crossbars 434 and 435 and intermediate crossbars 436. A narrow ribbed bed plate 437 is positioned with its rear edge closely overlying the roller 215 so that it serves as a wax scraper. Forwardly of the plate 437 a transversely ribbed bed plate 438 is mounted and forwardly of the plate 438 there is a longitudinally grooved bed plate 439. Forwardly of the plate 439 a row of pivoted bottom sealing fingers 440 are provided for engagement with the bottom of the wrapped articles. Forwardly of the fingers 440 a bridging plate 441 overlies the rear end of the bottom belt N of the cooling section E. The pivoted sealing fingers 440 are pivoted upon a transverse tubular heater 442 for independent pivotal movements.

Electrical heaters 443 are attached in a suitable manner to the underside of the bed plate 438. Similar heaters 444 are attached to the underside of the bed plate 439. The bed plates 438 and 439, together with the sealing fingers 440 and bridging plate 441, are supported on bars of heat insulating material 446 attached to the frame crossbars 434, 435 and 436. As shown in Fig. 7, the narrow rear bed plate 437 has a flange 437 attached to the rear crossbar 435 of the bed supporting frame and, in order to minimize the transfer of heat to the roller 215, a strip of insulating material 448 is interposed between the flange 437 and the crossbar 435.

The tubular heater 442 is supported at its ends upon brackets 449 attached to one of the intermediate crossbars 436. As shown in Fig. 19, the brackets 449 have upwardly opening bearing recesses 450 which receive the ends of the heater 442, which are held in place by retaining plates 451 which are flush with end portions of the bed plate 439. The brackets 449 bridge the space between the bed plate 439 and the plate 441 at the opposite side edges of the bed, the brackets having top portions 452 extending to adjacent the plate 441 and flush therewith.

The sealing fingers 440 have convex top faces 453 that are engageable with the undersides of articles such as bread loaves to press the overlapping edges of the wrapper against the bottom

12

of the article, while applying heat thereto, to seal the same. Adjacent their forward ends the fingers 440 have downwardly projecting lugs 454 which bear upon the free end portions of leaf springs 455 that are attached to the insulating bar 446 that is attached to the forward crossbar 434 of the bed supporting frame. Downward pressure of articles passing over the convex faces 453 of the fingers causes the fingers to be moved downwardly, deflecting the springs 455. The downwardly curved forward ends of the fingers 440 underlie the rear edge of the bridging plate 441 against which the forward ends of the fingers are normally held by the spring 456. The forward ends of the fingers 440 have notches 456 to receive the springs 455 when the fingers are moved downwardly.

In order to minimize the transfer of heat from the sealing section to the conveyor belt N forming the bed of the cooling section E, a strip 457 of insulating material is interposed between the top of the springs 455 and the underside of the plate 441.

Adjacent opposite side edges thereof the bed plate 438 has longitudinal grooves 458 into which wax melted from wrappers is drained and the grooves 458 are provided with openings 459 to discharge the melted wax. The bed plates 438 and 439 are spaced apart to provide an air gap 30 and reduce heat conduction when the heaters of one of the plates are disconnected, the plate having spaced fingers 460 bridging the gap.

Beneath the sealing bed a drip tray 461 is provided to catch any wax dripping from the bed plates so as to prevent the wax from dripping onto the drape table. The drip tray is detachably supported upon L-shaped studs 462 that are slidably mounted in brackets 463 attached to the front and rear crossbars 434 and 435 of the bed supporting frame. Springs 464 acting upon the studs 462 yieldingly clamp the corners of the tray 461 against the bottom of the brackets 463. The tray can be readily removed for emptying and cleaning by turning the studs 462 at one side of the frame out of engagement with the undersides of the tray.

In order to further limit the heating of the frame and the parts of the mechanism below the discharge runway, the bed sections are narrower than the space between the frames and between the bed sections and the side frame members. Grills 465 are mounted on the crossbars of the bed supporting frame, the spaces between the bed and side frame members providing ventilation between the bed and side frame members. The grill 465 provides ventilation between the bed and drape table to prevent heating of the wrapper web being fed over the drape table, which may be adjusted to a position fairly close to the discharge runway, and the grill provides a convenient support onto which articles can be moved from the folding and sealing section when the folder plates are swung to open position to permit removal of an improperly wrapped article.

The bed of the cooling section E which is formed by the belt conveyor N, which is preferably in the form of a woven wire belt, is also detachably mounted on the frame, being supported by a cross frame member 466 that is in the form of a wide downwardly facing channel and that is attached to the side members of the frame I by bolts 467. The conveyor N is supported upon longitudinal rods 468 that extend through blocks 469 that are suitably attached by welding, or the like, to the cross member 466.

The rods 468 pass through the blocks 469 and are held against endwise movement in the blocks by screws 470. The belt N has a drive pulley 471 at its rear end that is driven through the gears 11 and that is supported by bearing blocks 472 that are secured to the rear ends of the rods 468 by screws 473.

The conveyor N has a front idler pulley 474 that is journaled in bearing members 475 that are slideable on the forward ends of the supporting rods 468. The forward ends of the rods 468 are threaded and receive nuts 477 that bear against the rear faces of the bearing members 475 and which may be turned to move the pulley 474 forwardly to tighten the belt N. The bearing members 475 project beyond the end of the belt N and support a hollow refrigerated bed plate 478 that is attached to the members 475 by screws 479. The belt conveyor N has a bed plate 480 beneath the top run of the belt that is supported upon blocks 481 that are mounted on the rods 468, the blocks 481 being secured in adjusted position on the rods 468 by means of screws 482. The refrigerated plate 478 is level with the top run of the belt N and wrapped articles are moved across the plate 478 onto a roller bed 483 detachably supported on the bed plate 478. The roller bed has an angle bar 484 extending across its rear end that is provided with vertical slots 485 in its depending vertical flange which engage with bolts 486 attached to the bed plate 478. The bolt and slot connection between the roller bed 483 and the bed plate 478 permits the roller bed to be removed by lifting it off the bolts. The grill 465 extends past the sealing section and terminates at the rear side of the cross member 466. Forwardly of the grills the spaces between the belt N and side members of the frame 1 are bridged by aprons 487 that overlie the ends of the cross member 466 and are attached thereto.

The side folding and heating plates, together with the side belts P, are attached to and movable laterally with the side rails 158 which are supported upon the frame 1 adjacent the front and rear ends thereof. As shown in Fig. 2, shafts 490 and 490a adjacent the front and rear ends of the frame 1 are provided with right and left screws and serve to simultaneously adjust the side rails and attached parts toward and away from the center line of the machine. The forward ends of the side rails 158 travel with nuts 491 on the front screw shaft and the rear ends thereof travel with nuts 491a on the rear screw shaft 490a. The hand-wheel 24 drives the shaft 490 through a sprocket chain 492 and the shaft 490a is driven by a sprocket chain 493 connecting it to the shaft 490. As shown in Fig. 25, the front shaft 490 is journaled in standards 494 detachably secured to the cross frame member 463 and alongside the screw shaft 490 there is mounted a weight supporting crossbar 495 having a horizontal top edge upon which rollers 496 attached to the bars 158 travel. As best shown in Fig. 26, the bar 495 is attached to flanges 494a of the standards 494 by bolts 497 which extend through vertical slots 498 in the flange 494a. The opposite ends of the bar 495 can be independently adjusted to level the bar by loosening the bolts 497 and adjusting screws 499 carried by the bar 495 which bear against the top edges of the flanges 494a. The rear screw shaft 490a is journaled in a standard 500 detachably mounted upon the rear end of the frame 1 and a weight supporting crossbar 495a forming a track for

rollers 496a on the nuts 491a is mounted on the standards 500 in a manner similar to the mounting of the bar 495 on the standards 494.

The side rails 158 are detachably connected to the nuts 491 by means of slotted plates 501 and to the nuts 491a in a similar manner. One of the nuts 491 may be provided with a pointer 502 which travels over a graduated scale 503 on the bar 495 to indicate the adjustment of the side rails 158. All of the weight of the side rails 158, and of the parts mounted thereon is imposed upon the crossbars 495 and 495a independently of the screw shafts 490 and 490a so that sagging of the shafts and difficulty in turning the same to adjust the side members is avoided.

By detaching the standards 494 and 500 from the frame, the overhead pusher conveyor M, together with the folder plates 410 and 413 and side belts P carried on the side frame members 158, may be removed as a unit. Also, these parts may be assembled on the standards 494 and 500 before mounting on the frame 1.

In order to prevent the articles from being lifted off of the bed of the discharge runway by the engagement of the end folder with the slots of the folding plates, and to insure sufficient pressure against the heated bottom plates to effect sealing of the overlapping portions of the wrapper across the bottom of the package, it is desirable to provide a light pressure on the tops of the articles during their passage through the folding and heating channel. This pressure is exerted through a jointed hold-down bar that extends longitudinally of the runway centrally thereof. This bar comprises front, rear and intermediate sections 504, 505 and 506 which are flexibly connected by means of short links 507. It is desirable that the hold-down bar be normally supported in substantially horizontal position and that the pivoted joints connecting the sections permit upward movement of the jointed ends but not downward movement below a horizontal position. To this end, the adjoining ends of sections at each of the joints are provided with two stop plates 508 and 509 each of which is attached at one end to the top of one of the sections and extends across the joint between the sections, having its opposite end overlying the adjoining section but free from attachment to the said adjoining section. The plates 508 and 509 permit the hold-down to yield in an upward direction at the joints during passage of an article beneath the bar, and normally hold the sections in alignment in horizontal position as shown in Fig. 27.

A link 510 is connected to the forward end of the forward section 504 and has an elongated vertical slot 511 in its upper end which receives a pin 512 on an arm 513 attached to a collar 514 that is pivotally supported upon the forward screw shaft 490. A standard 516 is attached to the rear end of the section 505 and has an elongated vertical slot 517 that receives a pin 512a on an arm 518 that is attached to a collar 519 that is pivotally supported on the cross shaft 214. The pins 512 and 512a are identical latch pins providing a quick detachable connection for opposite ends of the sectional hold-down. As shown in Fig. 30, these pins are carried by the free ends of leaf springs 515 attached to the hold-down supporting arms. The collar 519 has an upwardly extending arm 520 which is connected by an extensible link 521 with a downwardly extending arm 522 on the collar 514. The collar 519 has a downwardly extending arm 523

15

to which is pivotally connected a horizontal rod 524 that is slidably mounted in the standard 500. To the rear of the standard 500 the rod 524 is provided with a handle 525 which can be gripped to move the rod 524 forwardly or rearwardly to raise or lower the hold-down. In order to releasably hold the adjusting rod 524 in adjusted positions, the rod 524 has a notched sleeve 526 that is slidable in the standard 500 and that is engaged with a spring pressed detent 527 which serves to releasably hold the rod 524 in adjusted position.

The rear end of the section 505 of the hold-down is curved upwardly as indicated at 528 to guide the article being wrapped into engagement with the under side of the bar. By reason of the rigid connection of the standard 516 to the section 505, thrust of the article on the curved end 528 tends to swing the entire hold-down as a unit in the direction of movement of the article which is crowded under the curved entrance portion 528 into engagement with the under side of the hold-down. The movement of the hold-down due to engagement of the article with the end portion 528 acts to raise the section 505 bodily, swinging the arm 518 upwardly, which causes the forward supporting arm 513 to be moved simultaneously in an upward direction, lifting the hold-down bodily. After the article has passed the rear section 505 the hold-down may drop by gravity as shown in dotted lines in Fig. 17. By adjusting the length of the link 521 the inclination of the jointed bar to the runway may be changed.

It is to be understood that in accordance with the provisions of the patent statutes, variations and modifications of the specific devices herein shown and described may be made without departing from the spirit of the invention.

What I claim is:

1. In a wrapping machine of the type in which the leading end of a web of wrapping material is applied to an article as it is delivered to an elevator and is wrapped about the article during upward movement of the elevator, a discharge runway comprising a horizontal bed having its rear end positioned to receive articles from the elevator and spaced parallel side rails above the bed, a top end folder plate and a bottom end folder plate carried by each rail and disposed end to end, the top end folder plates being positioned over the elevator and the bottom end folder plates being positioned alongside the rear end of said bed, the two folder plates on each side being rigidly connected together, a vertical hinge connecting the forward ends of the bottom end folder plates to the side rail, means for adjustably securing the rear ends of the top folder plates to said rail to vary the spacing of the rear ends of said plates.

2. In a wrapping machine of the type in which the leading end of a web of wrapping material is applied to an article as it is delivered to an elevator and is wrapped about the article during upward movement of the elevator, a discharge runway comprising a horizontal bed having its rear end positioned to receive articles from the elevator and spaced parallel side rails above the bed, bottom end folder plates on opposite sides of said runway forwardly of said elevator, said bottom folder plates being hinged at their forward ends to said rails to swing about vertical axes, a longitudinal bar attached to the upper portion of each of said bottom folder plates and projecting rearwardly past the rear ends there-

16

of, top folder plates attached to said bars rearwardly of said bottom folder plates, laterally adjustable stops limiting the inward movements of the rear ends of said bars, and releasable locking means for holding said bars against said stops in different positions of angular adjustment with respect to said side rails.

3. In a wrapping machine of the type in which the leading end of a web of wrapping material is applied to an article as it is delivered to an elevator and is wrapped about the article during upward movement of the elevator, a discharge runway comprising a horizontal bed having its rear end positioned to receive articles from the elevator and spaced parallel side rails above the bed, bottom end folder plates on opposite sides of said runway forwardly of said elevator, said bottom folder plates being hinged at their forward ends to said rails to swing about vertical axes, a longitudinal bar attached to the upper portion of each of said bottom folder plates and projecting rearwardly past the rear ends thereof, laterally adjustable stops interposed between the rear ends of said bars and said side rails to limit inward movement of said bars, releasable locking means for holding said bars against said stops in different positions of angular adjustment with respect to said rails, and top folder plates attached to said bars rearwardly of said bottom folder plates, said top folder plates being mounted for lateral and angular adjustment on said bars whereby said top folder plates may be secured in parallel relation in different positions of angular adjustment of said bars.

4. In a wrapping machine of the type in which the leading end of a web of wrapping material is applied to an article as it is delivered to an elevator and is wrapped about the article during upward movement of the elevator, a discharge runway comprising a horizontal bed having its rear end positioned to receive articles from the elevator and spaced parallel side rails above the bed, folder plates carried by each rail and disposed end to end, the folder plates on one side being rigidly connected together, a hinge connecting the rigidly connected plates to a side rail to swing laterally outwardly, a laterally adjustable stop for limiting the inward movement of the free end of the rigidly connected folder plates, and means for releasably locking said plates in stop engaging position.

5. In a wrapping machine a frame having front and back top members with horizontal top edges, crossbars connecting said frames adjacent their top edges, a runway comprising a horizontal bed narrower than the frame and supported on said bars, side rails supported above said bed, folder plates and article guide members carried by said rails, vertical hinges connecting said folder plates to said side rails upon which said plates may swing laterally to afford access to said runway, locking means for releasably holding said plates in operative position, and grills supported in the spaces between the side edges of said bed and the front and back frame members.

6. In a wrapping machine having front and back frame members and a folding and sealing channel between the top portions of said frame members, a rectangular frame detachably secured to said frame members and having spaced crossbars extending across the space between said frame members, heat insulating supports carried by said crossbars, sealing channel bed plates narrower than the space between said frame members and mounted on said supports, heaters car-

ried by said plates, and grills mounted on said crossbars and bridging the spaces between said plates and frame members.

7. In a wrapping machine having front and back frame members and a folding and sealing channel between the top portions of said frame members, a rectangular frame detachably secured to said frame members and having spaced crossbars extending across the space between said frame members, heat insulating supports carried by said crossbars, sealing channel bed plates narrower than the space between said frame members and mounted on said supports, heaters carried by said plates, and a drip tray detachably secured to said rectangular frame and underlying said bed plates.

8. In a wrapping machine having front and back frame members and a folding and sealing channel between the top portions of said frame members, a rectangular frame detachably secured to said frame members and having spaced crossbars extending across the space between said frame members, heat insulating supports carried by said crossbars, sealing channel bed plates narrower than the space between said frame members and mounted on said supports, drain openings in said plates and drain grooves leading to said openings, and a drip tray detachably secured to said rectangular frame and underlying said drain openings.

9. In a wrapping machine a frame, an article discharge runway having an article supporting bed, spaced crossbars carried by the frame above said bed, side rails mounted above the bed for lateral adjustment and article guide members carried by said side rails, transverse shafts mounted in said frame and each having right and left hand screw portions, said shafts being adjacent and parallel to said crossbars, nuts mounted on said screw portions of the shafts and attached to said side rails, said nuts being supported on said crossbars and receiving the threaded portions of said shafts, and means for adjusting said crossbars vertically.

10. In a wrapping machine a frame, an article discharge runway having an article supporting bed, spaced crossbars carried by the frame above said bed, side rails mounted above the bed for lateral adjustment and article guide members carried by said side rails, transverse shafts

50

mounted in said frame and each having right and left hand screw portions, said shafts being adjacent and parallel to said crossbars, nuts mounted on said screw portions of the shafts and attached to said side rails, said nuts being supported on said crossbars and receiving the threaded portions of said shafts, a pointer carried by one of said nuts and overlying a side face of the crossbar upon which the nut is supported, and a graduated scale on said side face for indicating the adjustment of said side rails.

11. In a wrapping machine having front and back frame members provided with substantially horizontal top edges and a folding and sealing channel between the top portions of said frame members, horizontal cross bars extending across the space between said frame members, heat insulating supports carried by said crossbars, a sealing channel bed plate narrower than the space between said frame members and mounted on said supports, a heater carried by said plate, and grills carried by said crossbars and bridging the spaces between said plate and the top edges of said frame members.

12. In a wrapping machine having front and back frame members provided with substantially horizontal top edges and a folding and sealing channel between the top portions of said frame members, a rectangular frame detachably secured to said frame members and extending across the space between the top portions thereof, heat insulating supports carried by said frame, a sealing channel bed plate mounted on said supports, said plate being narrower than the space between said frame members and spaced from each frame member, a heater carried by said plate, and grills mounted on said frame and bridging the spaces between said plate and the top edges of said frame members.
